UNITED STATES PATENT OFFICE.

JOHN FLAMMANG, OF ST. LOUIS, MISSOURI, ASSIGNOR TO OTTMAR G. STARK, OF ST. LOUIS, MISSOURI.

PROCESS OF MAKING PISTONS.

1,344,875.

Specification of Letters Patent. Patented June 29, 1920.

Application filed May 23, 1918. Serial No. 236,190.

To all whom it may concern:

Be it known that I, JOHN FLAMMANG, a citizen of the United States, residing at the city of St. Louis and State of Missouri, have 5 invented a new and useful Process of Making Pistons, of which the following is a specification.

This invention relates to the art of manufacturing pistons.

10 An object of the invention is to improve the art of manufacturing pistons whereby pistons may be produced that will impart uniform pressure against the cylinder wall all around by the resiliency of the metal of 15 which the pistons are composed, thus dispensing with the necessity of using piston rings or packing in connection with the pistons.

Additional objects and various advantages will appear from the following description in which reference is made to the drawings illustrating a piston in several stages of its construction in accordance with the present invention, and in which—

25 Figure 1 is a view partly in section, illustrating a form of casting from which the piston is made.

Figs. 2 and 3 are views illustrating the casting after the upper portion thereof has 30 been divided into segmental sections and the holes for the wrist pin have been formed.

Fig. 4 is a view illustrating the casting after it has been treated to cause the resiliency of the metal to close the openings 35 formed by cutting the upper portion of the piston body into segmental sections.

Fig. 5 is an elevation of the piston body after it has been subjected to additional treatment.

40 Fig. 6 is a view of the piston body having the wrist pin mounted therein, whereby the material is placed under tension so that when the piston is applied within the cylinder the resiliency of the metal will press the 45 segmental sections of the piston against the cylinder wall.

Fig. 7 is an elevation of the piston body under compression.

Fig. 8 is an elevation of the finished piston 50 having the top or head plate in connection with the piston body.

Fig. 9 is a view of the finished piston within a cylinder.

The piston body is made from a casting 55 including a lower ring 1, an upper ring 2,

connections 3 integrally uniting the lower and upper rings, and bosses 4 through which the holes for the wrist pin are formed.

By my present invention the upper ring 2 of the piston body is divided into segmental sections, one of which is integrally united with each of the connections 3. The connections 3 also constitute supports for the free ends of the segmental sections so that both ends of each segmental section are 65 firmly and rigidly supported. The segmental sections are formed by horizontal cuts 5 and inclined or oblique cuts 6 extending from the ends of the cuts 5 to the upper edges of the upper ring. This leaves 70 one end of each of the segmental sections integrally united with one of the connections, and the opposite end of each segmental section overlying a part of an adjacent connection 3. As shown the cuts 6 are oblique 75 or inclined relative to the axis of the piston, so that the ends of the segmental sections are overlapping. The piston body is then subjected to treatment, preferably by heat, to change the molecular arrangement of the 80 upper ring 2 so that the free ends of the segmental sections will press upon the adjacent portions of the connections 3 and thus close the cuts 5, as shown in Fig. 4. This treatment may be effected by mechanically 85 pressing the free ends of the segmental sections to the positions desired and, while the material is held in that position, heating the piston to a dull red heat to change the molecular arrangement and set the material in 90 that shape. After that has been done the upper edge or end of the piston body is ground or finished to provide a properly smooth surface upon which the removable top or head plate of the piston may be 95 mounted.

At a desired time relative to the above stages of treatment, the holes 7 for the wrist pins are formed through the connections 3 and the bosses 4. As shown and as preferred, the holes 7 are inclined inwardly and downwardly so that when the wrist pin 8 is applied therein the connections 3 will be sprung and the segmental sections of the upper ring spaced apart.

Either before or after the wrist pin is placed in the casting the exterior surface of the piston body is finished to a size in which the diameter of the lower ring 1 is slightly smaller than the diameter of the 110

cylinder for which the piston is intended, and in which the radii of the arcs of the connections 3 are also shorter than the radii of the cylinder in which the piston is to be mounted. The upper ring comprising the segmental sections above described is compressed to the position which it will occupy when placed in the cylinder and, while under compression, is finished to the same diameter as the diameter of the cylinder in which the piston is to operate. After being finished the head or top plate 9 is removably connected to the upper segmental sections of the piston. The connection may be effected in any desired manner as by forming an interlocking tongue and groove connection 10 between the top plate and the upper portion of the piston, or by the employment of locking keys 11 engaging in slots in the upper ring of the piston and in grooves in the top or head plate; or, if preferred, both of these connections may be employed as illustrated in Fig. 9.

The mounting of the wrist pin 8 in the inclined holes 7 retains the connections 3 in their sprung shape permanently so that mechanical pressure is applied to the connections 3 causing the full force of the resiliency thereof to be exerted upon the segmental sections of the upper ring.

Since the segmental sections of the upper ring have their ends approximately in the same vertical plane with the lines of expanding force, that is in approximately the same vertical plane with the axis of the wrist pin, it is clear that uniform or approximately uniform pressure will be exerted against the cylinder wall all around when the piston is placed therein. As shown in Fig. 8 the diameter of the top or head plate is the same as that of the cylinder in which the piston is to be mounted, while the diameter of the upper portion of the piston body when free from compression is slightly in excess of that of the head plate and also in excess of the diameter of the cylinder; although when the piston is mounted in the cylinder the upper portion of the piston is compressed as shown in Fig. 9.

Preferably, the ends of the segmental sections of the upper portion of the piston interlock so that the free end of each section will be held in annular alignment with the end of the adjacent section which is integral with the connection 3.

It is apparent that the order in which many of the various steps of the process are formed is immaterial and may be varied without in the least departing from the principle of the invention, as set forth in the appended claims.

What I desire to secure by Letters Patent, is:—

1. The process of making a piston which

consists in forming a piston body with an upper ring and a lower ring, which are integrally united; splitting the upper ring to form segmental sections having overlapping ends; and treating the material to close the spaces formed when the upper ring is split in the segmental sections.

2. The process of making a piston which consists in forming a piston body of a lower ring, an upper ring, and connections integrally uniting the upper and lower rings; splitting the upper ring into segmental sections which overlap said connections; and treating the piston body to cause the segmental sections to contact with said connections to close the spaces formed by splitting the upper ring.

3. The process of making a piston which consists in forming a piston body of a lower ring, an upper ring, and connections integrally uniting the upper and lower rings; splitting the upper ring into segmental sections which overlap said connections; treating the piston body to cause the segmental sections to contact with said connections to close the spaces formed by splitting the upper ring; drawing the segmental sections of the upper ring toward each other to place the material under tension; and finishing the piston body to a size in which the upper ring while compressed under tension is of the same diameter as the diameter of the cylinder for which the piston is intended.

4. The process of making a piston which consists in forming a piston body of a lower ring, an upper ring, and connections integrally uniting the upper and lower rings; splitting the upper ring into segmental sections which overlap said connections; treating the piston body to cause the segmental sections to contact with said connections to close the spaces formed by splitting the upper ring; drawing the segmental sections of the upper ring toward each other to place the material under tension; and finishing the piston body to a size in which the upper ring while compressed under tension is of the same diameter as the diameter of the cylinder for which the piston is intended, and in which the diameter of the lower portion of the piston body is less than the diameter of the cylinder for which the piston is intended.

5. The process of making a piston which consists in forming a piston body of a lower ring, an upper ring, and connections integrally uniting the lower and upper rings; splitting the upper ring into segmental sections which overlap each other; treating the segmental sections to close the spaces formed by splitting the upper ring; drawing the segmental sections of the upper ring toward each other to place the material under tension; finishing the piston to a size in

which the upper ring while compressed under tension is of the same diameter as the diameter of the cylinder for which the piston is intended; and mechanically holding 5 the upper portion of the piston body under tension.

6. The process of making a piston which consists in forming a piston body of a lower ring, an upper ring, and connections integrally uniting the upper and lower rings; splitting the upper ring into overlapping segmental sections which overlap the connections between the upper and lower rings; treating the upper portion of the piston to 10 close the spaces between the segmental sections and the connections; drawing the segmental sections of the upper ring toward each other to place the material under tension; finishing the piston to a size in which 15 20 the upper ring while under tension is of the same diameter as the diameter of the cylinder for which the piston is intended; and mechanically holding said connections permanently under tension.
- 25 7. The process of making a piston which consists in forming a piston body of a lower ring, an upper ring, and connections integrally uniting the upper and lower rings; splitting the upper ring into 30 overlapping segmental sections which overlap the connections between the upper and lower rings; treating the upper portion of the piston to close the spaces between the segmental sections and the connections; drawing the segmental sections of the upper ring toward each other to place the material under tension; finishing the piston to a size in which the upper ring while under tension is of the same 35 40 diameter as the diameter of the cylinder for which the piston is intended; and in which the diameter of the lower portion of the piston body is less than the diameter of the cylinder for which the piston is intended; and

mechanically holding said connections permanently under tension. 45

8. In the process of making a piston, the steps of causing a portion of the piston to press against the wall of the cylinder by the resiliency of the material of the piston, 50 which comprises splitting the upper portion of the piston to form overlapping segmental sections; compressing the overlapping segmental sections; and forming the overlapping sections with the same radius 55 of curvature as the radius of curvature of the cylinder for which the piston is intended, while said sections are compressed.

9. In the process of making a piston, the steps of causing a portion of the piston to 60 press against the wall of the cylinder by the resiliency of the material of the piston, which comprises splitting the upper portion of the piston to form overlapping segmental sections; compressing the overlapping segmental sections; forming the overlapping sections with the same radius of 65 curvature as the radius of curvature of the cylinder for which the piston is intended, while said sections are compressed; and providing a top plate in connection with said overlapping sections. 70

10. In the process of making a piston, the steps of causing a portion of the piston to press against the wall of the cylinder by 75 the resiliency of the material of the piston, which comprises splitting the upper portion of the piston to form overlapping segmental sections; compressing the overlapping segmental sections; forming the overlapping sections with the same radius of 80 curvature as the radius of curvature of the cylinder for which the piston is intended, while said sections are compressed; and interlocking a top plate with said overlapping 85 sections.

JOHN FLAMMANG.
